US00D984722S

(12) **United States Design Patent** (10) **Patent No.:** **US D984,722 S**
Tang (45) **Date of Patent:** **** Apr. 25, 2023**

(54) **LAMP**

(71) Applicant: **Shenzhen JinDian Electronic Technology Co., Ltd.**, Shenzhen (CN)
(72) Inventor: **Shifu Tang**, Shenzhen (CN)
(73) Assignee: **SHENZHEN JINDIAN ELECTRONIC TECHNOLOGY CO., LTD.**, Shenzhen (CN)

(**) Term: **15 Years**

(21) Appl. No.: **29/808,362**

(22) Filed: **Sep. 18, 2021**

(51) LOC (14) Cl. **26-05**

(52) U.S. Cl.

USPC **D26/119; D26/72**

CLAIM

The ornamental design for a lamp, as shown and described.

DESCRIPTION

FIG. 1 is a perspective view of a lamp showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the lamp that form no part of the claimed design.

1 Claim, 8 Drawing Sheets
